DESIGN FOR AN ATOMIZER

Carl W. Sundberg, Birmingham, Mich., assignor
to The DeVilbiss Company, Toledo, Ohio, a
corporation of Ohio

Application July 5, 1941, Serial No. 101,916

Term of patent 7 years

To all whom it may concern:

Be it known that I, Carl W. Sundberg, a citizen
of the United States, residing at 230 Linden
Street, Birmingham, in the county of Wayne and
State of Michigan, have invented a new, original,
and ornamental Design for an Atomizer, of which
the following is a specification, reference being
had to the accompanying drawing, forming part
thereof.

In the drawing:

Fig. 1 is a side elevational view of an atomizer
showing my new design; and Fig. 2 is a top
plan view thereof.

The essential features of my new design re-
side in the portions shown in full lines.

I claim:

The ornamental design for an atomizer, sub-
stantially as shown and described.

CARL W. SUNDBERG,
